Attorney

UNITED STATES PATENT OFFICE.

MOSES S. PITTMAN, OF SAN DIEGO, CALIFORNIA.

SAFETY GUARD FOR SPRING TRAPS.

Application filed December 29, 1920. Serial No. 433,895.

To all whom it may concern:

Be it known that I, MOSES S. PITTMAN, a citizen of the United States, residing at San Diego, in the county of San Diego and 5 State of California, have invented certain new and useful Improvements in Safety Guards for Spring Traps, of which the following is a specification.

My invention relates to improvements in 10 safety appliances for spring traps, and my object is to prevent injury to a person's fingers while setting said trap. The invention is intended more particularly for use on that type of spring trap employed in 15 catching mice and rats.

With the above object in view, reference will now be had to the accompanying drawing, in which:

Fig. 1 is a perspective view of the trap in 20 unset position and equipped with the safety appliance.

Fig. 2 is a plan view of the trap showing the safety device in operative position.

Referring more particularly to the several 25 parts of the trap, 2 designates a block or base upon which the working parts of said trap are mounted.

4 designates the jaw of the trap which is made of a section of wire bent into 30 rectangular form and having one end formed into an eye 6 through which the opposite end of said wire is passed. The jaw 4 is pivotally mounted at its rear end in bearings or staples 8, secured to the block 2.

35 10 designates a coil spring mounted upon the rear end of the jaw 4, and having one end 12 bearing upon said jaw 4 and the other end 14 bearing upon the base 2 of the trap, thus serving to tension said spring 10 40 when the jaw 4 is drawn backwardly preparatory to setting the trap.

16 designates a latch which holds the jaw 4 in set position, said latch being loosely connected at its rear end to a staple 17 secured 45 to the base 2.

18 designates the trigger of the trap, which has an end 20 bent upwardly at an angle to its main body and pivotally engaging a staple 22 secured to the block 2. The 50 end 20 of the trigger 18 has a perforation 21 for receiving the forward end of the latch 16 when the same is adjusted to hold the jaw 4 in set position. A bait holder 24 is struck

from the main portion of the trigger 18, to which any suitable bait (not shown) may 55 be secured.

All of the foregoing are of usual or any preferred construction.

The safety appliance constituting the important feature of the invention consists 60 of a, substantially, U-shaped element 25 formed, preferably, from a section of wire having an intermediate portion 26 provided with a V-shaped off-set 28 to fit over the latch 16 of the trap. The end members 30 65 of the element 25 are bent toward each other and mounted in bearings 34, and the extreme ends of said end members 30 are bent as indicated at 36 to prevent them from sliding out of their bearings 34. 70

In order to prevent the trap from being dragged away by a rodent caught by the foot, oppositely disposed fastening members 42 are provided to which a string or the like (not shown) may be attached and secured to 75 a nail or other fixed object.

In setting the trap, the jaw 4 is grasped and swung backwardly against the action of the spring 10, as shown on Fig. 2, after which the latch 16 is drawn down over said 80 jaw. The safety element 25 is then swung over the latch 16, the V-shaped portion 30 fitting over said latch where it is held by one hand while the other hand is used to engage the trigger 18 with the end of the 85 latch 16. It will thus be seen that the jaw 4 is held from being sprung while the trigger is being set and danger of injuring the fingers is thereby avoided.

From the foregoing description it will be 90 understood that I have provided a safety appliance which will prevent the trap from springing shut while being set, and one which cannot be dragged away by rodents caught in said trap, and while I have shown 95 the preferred embodiment of the invention, I reserve the right to make such changes as properly fall within the spirit and scope of the appended claim.

Having thus described my invention, what 100 I claim and desire to secure by Letters Patent, is:

In combination with a trap having a substantially rectangular spring actuated jaw and means including a latch for holding said 105 jaw in set position, a U-shaped safety device

adapted to engage two sides of the trap jaw and provided intermediate its ends with an off-set to engage and hold the latch while the trap is being set, and bearings fixed to 5 the base of the trap near the opposite sides thereof and in which the ends of said U-shaped safety device are operably mounted.

In testimony whereof I affix my signature, in the presence of two witnesses.

MOSES S. PITTMAN.
